Patented May 23, 1922.

*Inventor:
Sarah Glaser,
by Walter E. Lombard,
Atty.*

UNITED STATES PATENT OFFICE.

SARAH GLASER, OF BOSTON, MASSACHUSETTS, ASSIGNOR TO GLASER BROS., OF BOSTON, MASSACHUSETTS, A CORPORATION OF MASSACHUSETTS.

DESIGN FOR A FINGER RING.

60,985.

Specification for Design.

Patented May 23, 1922.

Application filed February 2, 1922. Serial No. 506. Term of patent 7 years.

To all whom it may concern:

Be it known that I, SARAH GLASER, a citizen of the United States, residing at Boston, in the county of Suffolk and State of Massachusetts, have invented a new, original, and ornamental Design for Finger Rings, of which the following is a specification, reference being had to the accompanying drawing, forming part thereof.

The figure is a perspective of a finger ring showing my new design.

I claim:

The ornamental design for a finger ring as shown.

SARAH GLASER.

Witnesses:

WALTER E. LOMBARD,
NATHAN C. LOMBARD.
